UNITED STATES PATENT OFFICE.

ROBERT MIEHLE, OF CHICAGO, ILLINOIS.

INKING MECHANISM FOR PRINTING-PRESSES.

1,382,525.

Specification of Letters Patent. Patented June 21, 1921.

Application filed September 25, 1918. Serial No. 255,551.

To all whom it may concern:

Be it known that I, ROBERT MIEHLE, a citizen of the United States, residing at Chicago, in the county of Cook and State of Illinois, have invented a certain new and useful Improvement in Inking Mechanisms for Printing-PresSES, of which the following is a clear, concise, and exact description, reference being had to the accompanying 10 drawings, forming a part of this specification.

My invention relates to inking mechanisms for printing presses and relates particularly to inking mechanisms for rotary 15 printing presses although certain features of the same are not limited to this use alone.

Generally the features of the invention relate to the inking mechanism and its related parts with a view toward simplicity, 20 compactness, ease of manipulation, adaptability to various inking conditions, including those present in a combination letter press printing and offset printing press, which may be operated to produce letter 25 press printing, offset printing or both, and accessibility for various purposes such as cleaning.

Certain features relate to the inking mechanism and controlling mechanism 30 therefor which is operative to meet various inking conditions all with a view toward the purposes above mentioned.

Certain other features relate to novel 35 constructions, combinations and arrangements whereby the ink distributing mechanism may be moved out of operative position for various purposes, such as cleaning, without undue exertion, adjustment or dis- 40 arrangement of the operative mechanism, all with a view toward the purposes above mentioned.

The invention in its preferred embodiment relates particularly to a combination letter press printing and offset printing machine, which may be adjusted for offset 45 printing or plate printing or both and as such embraces a form cylinder, a second form cylinder in printing relation with the first form cylinder, and inking means for 50 generally inking said form cylinders and common thereto. One of these form cylinders is preferably a single revolution cylinder and the other a two revolution cylinder, which arrangement has many advantages

unnecessary to be stated, and there is preferably tripping mechanism for breaking the printing relation of these cylinders.

Another feature relates to a novel construction and arrangement whereby the ink fountain and ink distribution mechanism 60 and supporting means therefor are so arranged that the rollers of the ink distributing mechanism may be assembled and removed from beneath the ink fountain whereby the space above the ink fountain may be 65 utilized for other purposes.

Other features relate to two ink distributing mechanisms adapted for movement in different paths to and away from their respective cylinders which are disposed in 70 printing relation whereby they are arranged compactly when in operative position and are easily accessible when in inoperative position. In the preferred embodiment an ink fountain and its related mechanism, preferably common to both ink distributing mechanisms, is disposed between the paths of the ink distributing mechanisms.

Another feature relates to a novel construction and arrangement whereby the ink 80 distributing mechanism of one form cylinder may be utilized to afford additional inking mechanism for the other form cylinder, preferably a form cylinder which is in printing relation with the aforesaid form cylinder. The second form cylinder is also preferably movable out of and into inking 85 relation with its ink distributing mechanism and the ink distributing mechanism of the other form cylinder when it is adjusted to 90 ink the same.

My invention has other and important characteristics and, in its various aspects, will be fully explained by reference to the 95 accompanying drawings and particularly pointed out in the claims. In the drawings Figure 1 is a view in side elevation, part broken away, of a printing press equipped in accordance with the preferred embodiment of my invention. Fig. 2 is a partial 100 end elevation of the same. Figs. 3, 4, 5, and 6 are partial side elevations similar to Fig. 1, and showing the parts in various positions.

In the drawings like characters of reference indicate like parts throughout the various views.

In the drawings 1 indicates a base. A

side frame 2 is secured upon the base 1 on each side thereof and extends upwardly therefrom to form supports for the various mechanisms of the machine. Corresponding horizontal slides 3 are formed in each side frame 2, and bearing blocks 4 are mounted for horizontal sliding movement in respective of said slides. The main form cylinder 5 has its ends journaled in respective bearing blocks 4 and is movable horizontally and transversely of the axis thereof by reason of the sliding engagement of the bearing blocks 4 with the slides 3 as hereinbefore described. Horizontally disposed coiled compression springs 6 have their opposite ends abutting respective side frames 2 and bearing blocks 4 and exert their influence to move the bearing blocks 4 and the cylinder 5 supported thereby against eccentric mechanisms 7 of usual construction whereby the cylinder 5 may be moved out of and into printing or operative position. The eccentric mechanisms 7 are provided with levers 8 which are operated by a press 25 driven tripping mechanism 8² of usual construction through connecting rods 8³.

Corresponding horizontal jaws 9 are formed in the side frames 2 and support a second form cylinder 10 by means of bearing blocks 11 in which the respective ends of the form cylinder 10 are journaled.

Corresponding vertical jaws 12 are also formed in the side frames 2 and have mounted therein respective bearing blocks 13 which support the impression cylinder 14 by reason of the fact that the ends of the cylinder are journaled in respective of said blocks. The bearing blocks 13 are held in proper position in their respective jaws by means of adjusting screws 15 screw threaded into respective side frames and abutting the under surface of respective bearing blocks 13, which are clamped against the adjusting screws 15 by means of clamping screws 16 which are screw threaded into spanners 17 and abut the upper surface of respective bearing blocks 13. The spanners 17 are secured to the respective side frames by means of bolts 18. The axes of the cylinders 5, 10 and 14 are parallel, and the cylinders 10 and 14 are disposed to contact the cylinder 5 at points lying on the side of a vertical plane passing through the axis of the cylinder 5 opposite the side of said vertical plane upon which the eccentric mechanism 7 is disposed. As a result of this arrangement the eccentric mechanisms 7 operate to move the cylinder 5 to and away from contact with, or operative relation with, both of the cylinders 10 and 14. Thus the operation of the eccentric mechanisms 7 to move the cylinder 5 to trip the same with respect to both of said cylinders or to restore the same into operative relation with both of the cylinders 65 as the case may be.

In the operation of the machine the matter to be printed is carried by the impression cylinder 14 from the feed-board 19 into impression relation with the form cylinder 5 and is thereafter discharged upon a sheet delivery mechanism 20. The usual mechanism is employed to drive the cylinders 5, 10, and 14, and the sheet delivery mechanism 20 in unison, and inasmuch as this mechanism is not involved in the present invention it needs no further illustration and description.

The cylinders 10 and 14 are preferably two revolution cylinders and the cylinder 5 is preferably a single revolution cylinder, and said cylinders 10 and 14 are preferably disposed in the upper portion of the sector of the cylinder 5 defined by the aforementioned vertical plane passing through the axis thereof. This arrangement leaves the lower portion of said sector of the cylinder 5 free for engagement with the ink distributing mechanism which will now be described. Journaled in and extending across the space between the side frames 2 is a rock shaft 21, and secured upon this rock shaft is a pair of roller frames 22 each of which is disposed adjacent a respective side frame 2 and on the inside thereof. The rock shaft 21 extends outwardly of the side frames and has secured thereon levers 23 which are disposed upon the outside of the respective side frames 2. The rock shaft 21 is disposed below the cylinder 5 and adjacent the vertical plane passing through the axis thereof and the levers 23 extend therefrom in the same general direction as do the roller frames 22 whereby upward movement of the levers 23 move the roller frames 22 toward the cylinder 5. Lock levers 24 are disposed on respective sides of the base 1, and are fixedly mounted on the ends of a rock shaft 24¹, journaled in said base 1, and extend upwardly from said shaft and have locking formations 25 formed at the upper ends thereof which are adapted to engage respective studs 26, secured at the free ends of respective levers 23, to lock the roller frames 22 in operative position. The ink distributing rollers for the cylinder 5 are carried by the roller frames 22 and comprise form rollers 27 arranged to contact the form 28 of the cylinder 5 when the roller frames 22 are locked in operative position and the cylinder 5 is positioned in operative position, and distributing rollers 29 intercontacting the form rollers to properly distribute and conduct the ink thereto. It will be noted that the cylinders 10 and 14 and the form rollers 27 are disposed to contact the cylinder 5 on the side of said vertical plane passing through the axis of the cylinder 5 which is opposite that upon which the eccentric mechanisms 7 are disposed, so that when the cylinder 5 is tripped as hereinbefore de- 130

scribed it is moved out of contact with the cylinders 10 and 14, as hereinbefore described, and the form rollers 27, see Fig. 3.

Secured upon each side frame on the outside thereof is a slide 30. Each slide supports the inner end of a roller frame 31 by means of an offset extension 32 of the roller frame 31 and a roller 33 rotatably mounted upon the inner end of the extension and engaging said slide. The roller frames 31 are disposed one on either side of the mechanism and a shaft 34 extends across the space between the same at the outer ends thereof and is journaled in each of the roller frames 31. A roller 35 is mounted at each end of the shaft 34 adjacent the respective roller frames 31 and is supported by a respective track 36. The tracks 36 are supported by the side frames in a manner to be hereinafter described and are disposed substantially parallel with the slides 30 whereby the roller frames 31 are supported for movement along said tracks and slides. The tracks 36 and the slides 30 are so disposed relatively to the form cylinder 10 that the roller frames 31 move along the same in a path which has a tangential relation with the said cylinder 10. See Figs. 3 and 4. The shaft 34 is provided at either end with a pinion gear 37 which is secured upon said shaft and meshes with racks 38 formed upon respective tracks 36. An operating handle 39 is secured at one end of the shaft 34 whereby the shaft 34 may be easily rotated to cause the pinions 37 to move the roller frames along the track. The outer ends of the tracks 36 are mounted for pivotal movement upon studs 40 mounted on respective extensions of the side frames 2, and the inner ends of said tracks 36 are supported upon eccentrics 41 which are secured upon a shaft 42 mounted for rotation in said extensions of the side frames 2 and extending across the space between the same. By rocking the shaft 42 the inner ends of the tracks 36 may be raised and lowered, which motion is transmitted to the outer end of the roller frames 31, when the same are in operative position, see Figs. 1 and 3, so that the roller frames 31 pivoting upon the rollers 33 move up and down in the path disposed radially with respect to the cylinder 10. The ink distributing mechanism of the cylinder 10 is mounted upon the roller frames 31 and comprises form rollers 43, arranged to contact the said form cylinder 10 when the roller frames 31 are in operative position, and intercontacting distributing rollers 44 arranged to distribute the ink properly throughout the form rollers. A locking lever 45, pivoted to the adjacent side frame, is provided to engage a stud 46, secured at the free end of the operating handle 39, with a locking formation 47 to position the shaft 34 to

hold the roller frames 31 with the rollers 33 in engagement with the inner ends of the respective slides 30. When locked in this position the roller frames 31 may be moved along their radial paths into and out of operative position relatively to the cylinder 10 by means of the shaft 42 and the eccentrics 41 mounted thereon.

Disposed across the space between the side frames 2 and having the ends thereof secured to said side frames is an ink fountain 48. This ink fountain is disposed so that the roller frames 31 may move out over the same, and so that the roller frames 22 may be moved downwardly past the same, see Fig. 4. Coöperating with the ink fountain 48 to charge both of the ink distributing mechanisms are two ductor rollers 49 and 50 and an ink transfer roller 51. The ductor roller 49 is mounted upon arm 52 which are secured to a rock shaft 53 journaled in the side-frames 2 and extending across the space between the same. The transfer roller 51 is carried by the roller frames 22 and is in contact with the adjacent intercontacting roller 29 of the ink distributing mechanism which inks the cylinder 5. By oscillating the shaft 53, when the ink distributing mechanism of the cylinder 5 is in operative position, the ductor roller 49 contacts the ink fountain 48 and the transfer roller 51 alternately to transfer ink from the ink fountain to said roller. The ductor roller 50 is carried by arms 54 which are secured upon a rock shaft 55 journaled in the roller frames 31 and extending across the space between the same. By oscillating the rock shaft 55 when both of the ink distributing mechanisms are in operative position the ductor roller 50 alternately contacts the transfer roller 51 and an adjacent intercontacting roller 44 of the ink distributing mechanism of the cylinder 10 to transfer ink from the transfer roller 51 to the intercontacting rollers 44 of said ink distributing mechanism.

The rock shafts 53 and 55 are oscillated from the press mechanism in the following manner. A gear 56 is mounted in driven relation with the cylinder 5, and through a gear train 57, with which it meshes, drives a gear 58 secured upon a cam shaft 59 journaled in the base 1. This gearing is so proportioned that the cam shaft 59 completes one revolution to each cycle of the machine or revolution of the cylinder 5. Secured upon the cam shaft 59 are two cams 60 and 61. Pivoted upon the base 1 is a lever 62 which has a roller 63 mounted at its free end which is adapted to engage the cam 60. The lever 62 is held with the roller 63 in engagement with the cam 60 by means of a rod 64, having its one end pivoted to the lever 62 and having its other end slidably engaged in an apertured bracket 65, and a coiled com-

pression spring 66 encircling said rod and abutting the bracket 65 and a shoulder of the rod with its opposite ends. A connecting rod 67 has its one end pivoted upon the lever 5 62, and has a downwardly facing notch 68 formed therein adjacent the opposite end thereof. An arm 69 is secured upon one end of the rock shaft 53, and is provided with a stud 70 which is adapted to be detachably 10 engaged by the notch 68 to form a driving connection between the connecting rod 67 and the arm 69. A lever 71 is pivoted on the adjacent side frame 2 and is provided at its free end with a roller 72 adapted for 15 engagement with the cam 61. The lever 71 is held with the roller 72 in engagement with the cam 61 by means of a rod 73, having its one end pivoted to the lever 71 and having its other end slidably engaged in an aper- 20 tured bracket 74, and a coiled compression spring 75 encircling said rod and abutting the bracket 74 and the shoulder of the rod with its opposite ends. A connecting rod 76 has its one end pivoted to the lever 71, and 25 has a downwardly facing notch 77 formed adjacent its other end, which notch is engageable with a stud 78 formed upon the free end of a swinging arm 79 pivoted upon the adjacent roller frame 31. The stud 78 is 30 also pivotally engaged by one end of a connecting link 80, which link has its other end pivoted to the adjacent arm 54. Through the mechanism just described the ductor rollers 49 and 50 are oscillated, as above 35 described, and the cams 60 and 61 are so timed that both of the ductor rollers 49 and 50 engage the transfer roller 51 at the same time, so that the ductor roller 50 may take ink from the transfer roller 51 before the 40 greater portion of the same has been transferred to the intercontacting rollers 29 of the ink distributing mechanism of the cylinder 5.

The gravital tendency of the connecting rods 67 and 76 ordinarily retain the notches 68 and 77 in engagement with respective studs 70 and 78. In order that the roller frames 22 may be lowered, as hereinbefore described, without interference with the ductor roller 49 a cam formation 81 is formed 45 on the adjacent locking lever 24, which cam formation engages a stud 82, formed on the connecting rod 67 adjacent the notch 68 thereof, when said locking lever 24 is moved 50 to unlocking position and raises said connecting rod 67 to disengage the notch 68 thereof from the stud 70. A retaining notch 83 is formed on this locking lever 24 at the high end of the cam formation 81 55 to unlock position and serves to engage the stud 82 to retain said locking lever in unlock- 60 position when the connecting rod 67 has been raised to disengage the notch 68 from the stud 70. See Fig. 4. It will be noted that 65 this locking lever 24 serves the double pur-

pose of locking the roller frames 31 in operative position and of controlling the press driven means for oscillating the ductor roller 49. The roller frames 22 and the levers 23 are counterbalanced by means 70 of a weighted extensions 84 of the levers 23 disposed on the side of the axis of the rack shaft 21 opposite that side on which the roller frames 22 and the levers 23 are disposed. The downward movement of the 75 roller frames 22 is limited by a stud 85 formed on the base 1 and adapted to engage one of the levers 23 as it is moved downwardly, see Fig. 4. A connecting link 86 has its upper end pivoted upon the locking 80 lever 45 and has a longitudinal slot 87 formed at its lower end, which slot engages the stud 88 formed at the notched end of the connecting rod 76. When the roller frames 31 are in operative position and the locking 85 lever 45 is engaged through its locking formation 47 with the stud 46 of the operating handle 39 the stud 88 idly engages said slot. See Fig. 1. When the locking lever 45 is 90 swung upwardly to unlock the operating handle 39 the lower end of the slot 87 engages the stud 88 to lift the connecting rod 76 to disengage the notch 77 thereof from the stud 78. This movement allows the free movement of the ductor roller 50 so that the 95 roller frames 31 may be moved outwardly along the slide 30 and the tracks 36, see Fig. 4. The unlocking movement of the lever 45 is limited by the shaft 89 of the cylinder 10 which projects into the path of the lever 45, 100 see Figs. 2 and 4. When the locking lever 45 abuts the shaft 89 the gravital tendency of the same retains it in this position, the pivotal connection of the link 86 with the lever 45 being disposed to exert a gravital 105 tendency in the same direction, see Fig. 4.

As hereinbefore stated the eccentric mechanisms 7 are provided with levers 8 which are operated by press driven tripping mechanisms 8² of usual construction through connecting rods 8³. During the normal operation of the machine the tripping mechanism 8² remains idle with the eccentric mechanisms 7 and their levers 8 in the position as shown in Fig. 1 to maintain the cylinder 5 110 in printing or operative position. When the tripping mechanism 8² is allowed to function to trip and the levers 8 are swung upwardly in a counter-clockwise direction to position the eccentric mechanisms 7 to allow the springs 6 to move the cylinder 5 out of operative position, see Fig. 3. A connecting rod 90 has its one end pivotally secured to arm 8 and has its other end pivotally secured to the free end of an arm 91, secured upon 115 the end of shaft 42, by means of a stud 92. As hereinbefore described eccentrics 41 are mounted upon the shaft 42 to control the position of the roller frames 31 in their radial path relatively to the cylinder 10 when 120 125 130

said roller frames are locked in operative position by the locking lever 45 hereinbefore described. By means of the connecting rod 90 and its related parts the rock shaft 42 is 5 oscillated back and forth as the adjacent arm 8 is moved to and from the position shown in Figs. 1 and 3, and the parts are so related that when the cylinder 5 is positioned in printing relation with the cylinders 10 and 14 and its related ink distributing mechanism the roller frames 31 are positioned to maintain the form rollers 43, carried thereby, in contact with the cylinder 10. See Fig. 1. When the adjacent arm 8 is positioned to 15 maintain the cylinder 5 out of contact with the cylinders 10 and 14 and its related ink distributing mechanism, *i. e.*, its tripped position, the roller frames 31 are positioned so that the form rollers 43 are out of contact 20 with the cylinder 10, as shown in Fig. 3. Thus when the cylinder 5 is tripped it is out of contact with the cylinders 10 and 14 and its related ink distributing mechanism, and the form rollers 43 are out of contact with 25 the cylinder 10.

Pivottally mounted upon the stud 92 of the arm 91 is a stop block 93. This stop block is provided with a pin 94 overlying the connecting rod 90 and adapted to engage the 30 same to limit the movement of the block in one direction, and a second pin 95 is formed on the arm 91 to limit the movement of the block in the other direction. When the pin 94 of the stop block 93 is engaged with the 35 connecting rod 90 and the cylinder 5 is tripped, see Fig. 3, the block lies in the path of a stud 96 mounted on the adjacent arm 52 and prevents the rock shaft 53 from being moved to contact the roller 49 with the 40 ink fountain 48 to prevent the ink distributing mechanisms from being charged. See Fig. 3. It will be noted that the spring 66 through its related parts provides the movement of the arms 52 toward the ink fountain and allows the path of movement of said arms to be shortened as described. When the cylinder 5 is positioned in 45 operative or printing position the block 93 is out of the path of movement of the stud 96 and allows the rock shaft 53 to be oscillated to contact the ductor roller 49 with the ink fountain. When the stop block 93 is thrown over into engagement with the pin 95 it does not lie in the path of the 50 stud 96 in any position of the cylinder 5 so that the ink distributing mechanisms may be charged, if it is so desired, while the press is tripped. See Fig. 5.

The weight of the roller frames 31 and the 55 rollers supported thereby is counterbalanced by means of rods 97 slidably engaging respective sockets 98, formed in the base 1, with their one end and having their other end pivotally engaged by studs 99 of respective tracks 36 and coiled compression

springs 100 encircling respective of said rods and abutting the base 1 and shoulders of the respective rods with their opposite ends. The lifting tendency of the springs 100 is not sufficient to raise the tracks 36 away from 70 the eccentrics 41 when the roller frames 31 are in operative position, see Fig. 1. To prevent the springs 100 from raising the tracks 36 out of engagement with the eccentrics 41 when the roller frames 31 are 75 positioned out of operative position, as shown in Fig. 4, the tracks 36 are provided with fingers 101 adapted to engage studs 102 affixed to adjacent side frames to prevent the tracks from being lifted above highest 80 position of the eccentrics 41 when the roller frames 31 are moved out of operative position as shown in Fig. 4.

It will be noted that the ink fountain 48 is so disposed that space is left between it 85 and the upper surface of the base 1. The inner surfaces of the side frames 2 are provided with tracks 103 upon which the rollers of the ink distributing apparatus may be rested and removed from the machine under the ink fountain 48, the side frames 2 being spaced sufficiently to allow the rollers to be thus removed. A roller 104 is shown in dotted lines in Figs. 1 and 2 resting upon said tracks 103. 95

The cylinder 10 is provided with moistening mechanism 105 of usual construction whereby the same may be used in offset printing though not limited to this type of 100 printing alone.

The form roller 43, which lies nearest the point of convergence of the cylinders 5 and 10, is provided with adjustable roller sockets 106 which are secured to respective roller frames 31 by means of headed screws 107 passing through slots 108 formed in the roller frames 31 and screw threaded into respective sockets 106 whereby the roller frames are clamped between respective sockets 106 and the heads of the respective 110 screws 107 to adjustably secure the sockets 106 to the respective roller frames. The slots 108 are so disposed as to allow adjustment of the sockets 106 to permit the supported form roller 43 to be positioned in 115 inking relation with the cylinder 10 or the cylinder 5, this roller being maintained in contact with the adjacent intercontacting roller 44 in either adjustment. Figs. 1, 3, and 4 show this roller in inking relation 120 with cylinder 10 and Fig. 6 shows the same in inking relation with cylinder 5. By this arrangement the ink of the cylinder 5 may be increased, if so desired, without unduly deranging the mechanism. When the mechanism is used in this adjustment the remaining form rollers 43 are removed and the cylinder 10 moved out of printing relation with the cylinder 5 by loosening screws 109 which secure spanners 110 to the outer ends 130

of respective jaws 9, which spanners maintain the bearing blocks abutting stop blocks 111 with cylinder 10 in printing relation with cylinder 5, and moving the bearing blocks 11 along the jaws 9 out of engagement with stop blocks 111. See Figs. 1, 2, 3, and 4. If the usual metal transfer surface is used on the cylinder 10, it is only necessary to remove the same from the cylinder 10 to discontinue the printing relation between cylinders 5 and 10. It will be noted that, when the form roller 43, above mentioned, is adjusted in inking relation with the cylinder 5, the movement of the cylinder 5 out of printing position moves the same out of inking relation with this roller 43 in the same manner as it moves out of inking relation with the form rollers. 27.

20 While I have herein shown and particularly described the preferred embodiment of my invention I do not wish to be limited to the precise details of construction shown as changes may readily be made without departing from the spirit of my invention, but having thus described my invention I claim 25 as new and desire to secure by Letters Patent the following:

1. A printing press including an ink distributing mechanism; a cylinder in operable relation with said ink distributing mechanism and movable out of and into operable relation with said ink distributing mechanism; a second ink distributing mechanism; 30 charging means for said ink distributing mechanisms; and mechanism for controlling said second ink distributing mechanism and said charging means and having connection with said cylinder and movable therewith and adapted to render said second ink distributing mechanism and said charging means inoperative when said cylinder is positioned out of operable relation with said first mentioned ink distributing mechanism.

40 2. A printing press including an ink distributing mechanism movably mounted and adapted to be moved into and out of operative position; means for charging said ink distributing mechanism and adapted to be rendered inoperative; and a locking means 45 for locking said ink distributing mechanism in position, said locking means having connection with said charging means and adapted to render said charging means inoperative when said locking means is moved to a certain position.

3. A printing press including an ink distributing mechanism movably mounted and adapted to be moved into and out of operative position; means for charging said ink distributing mechanism, and adapted to be rendered inoperative; and a locking means 50 for locking said ink distributing mechanism in operative position, said locking means having connection with said charging

means and adapted to render said charging means inoperative when said locking means is moved to unlocking position.

4. A printing press including an ink distributing mechanism movably mounted 70 and adapted to be moved into and out of operative position; a charging means therefor which is inclusive of an actuating pin and a press actuated connecting rod provided with a notch engageable with the pin to actuate 75 the same; means for locking said ink distributing mechanism in position, said locking means having connection with said connecting rod and adapted to disengage said notch from said pin when said locking means is moved to a certain position.

5. A printing press including an ink distributing mechanism movably mounted and adapted to be moved into and out of operative position; a charging means therefor 85 which is inclusive of an actuating pin and a press actuated connecting rod provided with a notch engageable with the pin to actuate the same; means for locking said ink distributing mechanism in operative position, said locking means having connection with said connecting rod and adapted to disengage said notch from said pin when said locking means is moved to unlocking position.

6. A printing press including an ink distributing mechanism; a charging mechanism therefor; and means including a locking means for said ink distributing mechanism for locking said ink distributing mechanism in operative position and adapted to render 100 said charging mechanism inoperative when said locking means is in unlocked position.

7. A printing press including a movably mounted cylinder; a movably mounted ink distributing mechanism; a charging means 105 therefor; means operative with the movement of the cylinder in one direction to render said charging means functionless; and means operative with the movement of said ink distributing mechanism in one direction 110 to render said charging means inoperative.

8. A printing press including a movably mounted cylinder; a movably mounted ink distributing mechanism therefor; a charging means therefor; means operative with the 115 movement of the cylinder in one direction to render said charging means functionless; and means operative with the movement of said ink distributing mechanism in one direction to render said charging means inoperative.

9. A printing press including an ink distributing mechanism; charging means therefor; a cylinder in operable relation with said ink distributing mechanism, and mov- 120 able out of operable relation with said ink distributing mechanism, said ink distributing mechanism being movably mounted and movable out of operative relation with said cylinder; means having connection with said 130

- cylinder and operable in unison therewith and adapted to render said charging means functionless when said cylinder is positioned out of operative relation with said ink distributing mechanism; and means for rendering said charging means inoperative and operable to render said charging means inoperative when said ink distributing mechanism is moved out of operative position.
- 10 10. A printing press including an ink distributing mechanism; charging means therefore; a cylinder in operative relation with said ink distributing mechanism and movable out of operative relation with said ink distributing mechanism, said ink distributing mechanism being movably mounted and movable out of operative relation with said cylinder; means having connection with said cylinder and operable in unison therewith and adapted to render said charging means functionless when said cylinder is positioned out of operative relation with said ink distributing mechanism; mean for locking said ink distributing mechanism in position; and a second means for rendering said charging means inoperative and having connection with said locking means and adapted to be positioned to render the charging means inoperative when said locking means is moved to a certain position.
- 15 11. A printing press including an ink distributing mechanism; charging means therefore; a cylinder in operative relation with said ink distributing mechanism and movable out of operative relation with said ink distributing mechanism, said ink distributing mechanism being movably mounted and movable out of operative relation with said cylinder; means having connection with said cylinder and operable in unison therewith and adapted to render said charging means functionless when said cylinder is positioned out of operative relation with said ink distributing mechanism; means for locking said ink distributing mechanism in operative position; and a second means for rendering said charging means inoperative and having connection with said locking means and adapted to be positioned to render the charging means inoperative when said locking means is moved to unlock position.
- 20 12. A printing press including an ink distributing mechanism; a cylinder; a second cylinder in operative relation with said first mentioned cylinder and said ink distributing mechanism and movable out of and into operative relation with said ink distributing mechanism and said first mentioned cylinder; a second ink distributing mechanism for said first mentioned cylinder and movable to and from operative relation with said first mentioned cylinder; means for controlling the position of said second ink distributing mechanism; a common charging means for said ink distributing mechanism; means for rendering said charging means functionless relatively to both ink distributing mechanisms; means for rendering said charging means functionless relatively to said second ink distributing mechanism; and connections between said first mentioned means and said second cylinder whereby they are movable therewith and whereby said charging means is rendered functionless and said second mentioned ink distributing mechanism is moved out of operative relation with its cylinder when said second cylinder is moved into inoperative position.
- 25 13. A printing press including an ink distributing mechanism; a cylinder; a second cylinder in operative relation with said first mentioned cylinder and said ink distributing mechanism and movable out of and into operative relation with said ink distributing mechanism and said first mentioned cylinder; a second ink distributing mechanism for said first mentioned cylinder and movable to and from operative relation with said first mentioned cylinder; means for controlling the position of said second ink distributing mechanism; a common charging means for said ink distributing mechanism; means for rendering said charging means functionless relatively to both ink distributing mechanisms; means for rendering said charging means functionless relatively to said second ink distributing mechanism; and connections between said first mentioned means and said second cylinder whereby they are movable therewith and whereby said charging means is rendered functionless and said second mentioned ink distributing mechanism is moved out of operative relation with its cylinder when said second cylinder is moved into inoperative position.
- 30 14. A printing press including a cylinder; an ink distributing mechanism for said cylinder; a support for said ink distributing mechanism adapted to allow movement of said ink distributing mechanism tangentially to and away from said cylinder and radially to and from said cylinder; a charging means for said ink distributing mechanism; means for controlling the tangential movement of said ink distributing mechanism; a separate means for controlling the radial movement of said ink distributing mechanism; means for rendering said charging means functionless and operable with one of said second and third mentioned means; and a second means for rendering said charging means inoperative and operable with the other of said second and third mentioned means.
- 35 15. A printing press including a cylinder; an ink distributing mechanism for said cylinder; a support for said ink distributing mechanism adapted to allow movement of said ink distributing mechanism tangentially to and from said cylinder and radially to and from said cylinder; a charging means

for said ink distributing mechanism; means for controlling the tangential movement of said ink distributing mechanism; a separate means for controlling the radial movement 5 of said ink distributing mechanism; means for rendering said charging means inoperative and operable with said second mentioned means; and a second means for rendering said charging means functionless and 10 having operative connection with said third mentioned means to operate in unison therewith.

16. A printing press including a cylinder; an ink distributing mechanism for said cylinder; a support for said ink distributing mechanism adapted to allow movement of said ink distributing mechanism tangentially to and from said cylinder and radially to and from said cylinder; a charging 15 means for said ink distributing mechanism; means for controlling the tangential movement of said ink distributing mechanism; a separate means for controlling the radial movement of said ink distributing mechanism; means for rendering said charging 20 means inoperative; a locking means for locking said second mentioned means in position, said locking means having connection with said charging means and adapted to render said charging means inoperative when 25 said locking means is moved to a certain position; and second means for rendering said charging means functionless and operable with said third mentioned means to operate 30 in unison therewith.

17. A printing press including a cylinder; an ink distributing mechanism for said cylinder; a support for said ink distributing mechanism adapted to allow movement of 40 said ink distributing mechanism tangentially to and from said cylinder and radially to and from said cylinder; a charging means for said ink distributing mechanism; means for controlling the tangential movement of said ink distributing mechanism; a separate 45 means for controlling the radial movement of said ink distributing mechanism; means for rendering said charging means inoperative; a locking means for locking said second mentioned means in operative position, said locking means having connection with 50 said charging means and adapted to render said charging means inoperative when said locking means is moved to unlock position; and another means for rendering said charging means functionless and operable with said third mentioned means to operate 55 in unison therewith.

18. A printing press including a cylinder; 60 an ink distributing mechanism for said cylinder; a support for said ink distributing mechanism adapted to allow movement of said ink distributing mechanism tangentially to and from said cylinder and radially to and from said cylinder; means for con-

trolling the tangential movement of said ink distributing mechanism; a separate means for controlling the radial movement of said ink distributing mechanism; tripping mechanism for controlling the impression relation between said cylinder and its complemental impression member; and a connection between said second mentioned means and said tripping mechanism whereby they are operated in unison and whereby 70 said ink distributing mechanism is moved away from said cylinder when the impression relation of said cylinder is broken by the operation of said tripping mechanism.

19. A printing press including a cylinder; 80 an ink distributing mechanism for said cylinder; a support for said ink distributing mechanism adapted to allow movement of said ink distributing mechanism tangentially to and away from said cylinder and radially to and from said cylinder; a charging 85 means for said ink distributing mechanism; means for controlling the tangential movement of said ink distributing mechanism; a separate means for controlling the 90 radial movement of said ink distributing mechanism; tripping mechanism for controlling the impression relation between said cylinder and its complemental impression member; means for rendering said charging 95 means functionless; and a connection between said tripping mechanism and said third mentioned means and said last mentioned means whereby said ink distributing mechanism is moved away from said cylinder and said charging means is rendered 100 functionless when the impression relation of said cylinder is broken by the operation of said tripping mechanism.

20. A printing press including a cylinder; 105 an ink distributing mechanism for said cylinder; a support for said ink distributing mechanism adapted to allow movement of said ink distributing mechanism tangentially to and away from said cylinder and radially to and from said cylinder; a charging 110 means for said ink distributing mechanism; means for controlling the tangential movement of said ink distributing mechanism; a separate means for controlling the 115 radial movement of said ink distributing mechanism; tripping mechanism for controlling the impression relation between said cylinder and its complemental impression member; means for rendering said charging 120 means inoperative and operable with said second mentioned means; another means for rendering said charging means functionless; and a connection between 125 said tripping mechanism and said third mentioned means and said last mentioned means whereby said ink distributing mechanism is moved away from said cylinder and said charging means is rendered functionless when the impression relation of 130

said cylinder is broken by the operation of said tripping mechanism.

21. A printing press including a cylinder; an ink distributing mechanism for said cylinder; a support for said ink distributing mechanism adapted to allow movement of said ink distributing mechanism tangentially to and away from said cylinder and radially to and from said cylinder; a charging means for said ink distributing mechanism; means for controlling the tangential movement of said ink distributing mechanism; a separate means for controlling the radial movement of said ink distributing mechanism; tripping mechanism for controlling the impression relation between said cylinder and its complemental impression member; locking means for locking said second mentioned means in position, said locking means having connection with said charging means and adapted to render said charging means inoperative when said locking means is moved to a certain position; another means for rendering said charging means functionless; and a connection between said tripping mechanism and said third mentioned means and said last mentioned means whereby said ink distributing mechanism is moved away from said cylinder and said charging means is rendered functionless when the impression relation of said cylinder is broken by the operation of said tripping mechanism.

22. A printing press including a cylinder; an ink distributing mechanism for said cylinder; a support for said ink distributing mechanism adapted to allow movement of said ink distributing mechanism tangentially to and away from said cylinder and radially to and from said cylinder; a charging means for said ink distributing mechanism; means for controlling the tangential movement of said ink distributing mechanism; a separate means for controlling the radial movement of said ink distributing mechanism; tripping mechanism for controlling the impression relation between said cylinder and its complemental impression member; locking means for locking said second mentioned means in operative position, said locking means having connection with said charging means and adapted to render said charging means inoperative when said locking means is moved to unlock position; another means for rendering said charging means functionless; and a connection between said tripping mechanism and said third mentioned means and said last mentioned means whereby said ink distributing mechanism is moved away from said cylinder and said charging means is rendered functionless when the impression relation of said cylinder is broken by the operation of said tripping mechanism.

23. A printing press including a printing

couple having a form cylinder in combination with a second form cylinder in printing relation with the aforesaid form cylinder; and inking means for generally inking said form cylinders and common thereto.

70

24. A printing press including a printing couple having a single revolution form cylinder in combination with a second form cylinder which is a two revolution cylinder in printing relation with the aforesaid form cylinder; and inking mechanism for generally inking said form cylinders and common thereto.

75

25. A printing press including a printing couple having a single revolution form cylinder in combination with a second form cylinder which is a two revolution cylinder in printing relation with the aforesaid form cylinder; inking means for generally inking said form cylinders and common thereto; and tripping mechanism for tripping the printing relation between said form cylinders.

80

26. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow movement of the same out of operative relation with its cylinder in a direction away from said point of convergence; a second ink distributing mechanism for said second form cylinder disposed adjacent said point of convergence on said one side and between said first mentioned ink distributing mechanism and said second form cylinder; and a support for said second ink distributing mechanism adapted to allow movement of the same out of operative relation with its cylinder in a direction away from said point of convergence.

95

27. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow arcal movement of the same out of operative relation with its cylinder in a direction away from said point of convergence, the focal point of said arc being disposed at the distant end of said ink distributing mechanism relatively to said point of convergence; a second ink distributing mechanism for said second form cylinder disposed adjacent said point of convergence on said one side and between said first mentioned ink distributing mechanism and said second form cylinder; and a support for said second ink distributing mecha-

nism adapted to allow movement of the same out of operative relation with its cylinder in a direction away from said point of convergence.

5 28. A printing press including a form cylinder; a second form cylinder disposed in printing relation with said first mentioned form cylinder; an ink distributing mechanism for said first form cylinder disposed
10 adjacent and on one side of the point of convergence of the peripheries of said cylinders; a support for said ink distributing mechanism adapted to allow movement of the same out of operative relation with its
15 cylinder in a direction away from said point of convergence; a second ink distributing mechanism for said second form cylinder disposed adjacent said point of convergence on said one side and between said first men-
20 tioned ink distributing mechanism and said second form cylinder; and a support for said second ink distributing mechanism adapted to allow movement of the same out of operative relation with its cylinder in a
25 direction tangential to said second form cylinder and away from said point of convergence.

29. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow arcal movement of the same out of operative relation with its cylinder in a direction away from said point of convergence, the focal point of said 40 arc being disposed at the distant end of said ink distributing mechanism relatively to said point of convergence; a second ink distributing mechanism for said second form cylinder disposed adjacent said point of convergence on said one side and between said first mentioned ink distributing mechanism and said second form cylinder; and a support for said second ink distributing mechanism adapted to allow movement of the same 45 out of operative relation with its cylinder in a direction tangential to said second form cylinder and away from said point of convergence.

30. A printing press including a form cylinder, a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow movement of the same out of operative relation with its cylinder in a direction away from said point of convergence; a second ink distributing

mechanism for said second form cylinder disposed adjacent said point of convergence on said one side and between said first mentioned ink distributing mechanism and said second form cylinder; and a support for 70 said second ink distributing mechanism adapted to allow movement of the same out of operative relation with its cylinder in a direction away from said point of convergence and angularly to the path of movement 75 of said first mentioned ink distributing mechanism.

31. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow arecal movement of the same out of operative relation with its cylinder in a direction away from said point of convergence, the focal point of said arc being disposed at the distant end of said ink distributing mechanism relatively to said point of convergence; a second ink distributing mechanism for said second form cylinder disposed adjacent said point of convergence on said one side and between said first mentioned ink distributing mechanism and said second form cylinder; and a support for said second ink distributing mechanism adapted to allow movement of the same out of operative relation with its cylinder in a direction away from said point of convergence and angularly to the path of movement of said first mentioned ink distributing mechanism.

32. A printing press including a form cylinder; a second form cylinder disposed in 105 printing relation with said first mentioned form cylinder; an ink distributing mechanism for said first form cylinder disposed adjacent and on one side of the point of convergence of the peripheries of said cylinders; a support for said ink distributing mechanism adapted to allow movement of the same out of operative relation with its cylinder in a direction away from said point of convergence; a second ink distributing 110 mechanism for said second form cylinder disposed adjacent said point of convergence on said one side and between said first mentioned ink distributing mechanism and said second form cylinder; and a support for 115 said second ink distributing mechanism adapted to allow movement of the same out of operative relation with its cylinder in a direction tangential to said form cylinder and away from said point of convergence 120 and angularly to the path of movement of said first mentioned ink distributing mechanism.

33. A printing press including a form cylinder; a second form cylinder disposed 130

in printing relation with said first mentioned form cylinder; an ink distributing mechanism for said first form cylinder disposed adjacent and on one side of the point 5 of convergence of the peripheries of said cylinders; a support for said ink distributing mechanism adapted to allow arcal movement of the same out of operative relation with its cylinder in a direction away from 10 said point of convergence, the focal point of said arc being disposed at the distant end of said ink distributing mechanism relatively to said point of convergence; a second ink distributing mechanism for said second 15 form cylinder disposed adjacent said point of convergence on said one side and between said first mentioned ink distributing mechanism and said second form cylinder; and a support for said second ink distributing 20 mechanism adapted to allow movement of the same out of operative relation with its cylinder in a direction tangential to said second form cylinder and away from said point of convergence and angularly to the 25 path of movement of said first mentioned ink distributing mechanism.

34. A printing press including a form cylinder; a second form cylinder disposed in printing relation with said first mentioned form cylinder; an ink distributing mechanism for said first form cylinder disposed adjacent and on one side of the point 30 of convergence of the peripheries of said cylinders; a support for said ink distributing mechanism adapted to allow movement of the same out of operative relation with its cylinder in a direction away from said point of convergence; a second ink distributing mechanism for said second form cylinder disposed adjacent said point of convergence on said one side and between said first mentioned ink distributing mechanism and said second form cylinder; a support for said second ink distributing mechanism adapted to allow movement of the same out of operative relation with its cylinder in a direction tangential to said second form cylinder and 35 away from said point of convergence; and an ink fountain common to said ink distributing mechanisms disposed between the paths of movement of said ink distributing mechanisms.

40 35. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing 45 mechanism adapted to allow arcal movement of the same out of operative relation with its cylinder in a direction away from said point of convergence, the focal point of said arc being disposed at the distant end of said ink distributing mechanism relatively to said point of convergence; a second ink distributing mechanism for said second form cylinder disposed adjacent said point of convergence on said one side and between said first mentioned ink distributing mechanism and said second form cylinder; a support for said second ink distributing mechanism adapted to allow movement of the same out of operative relation with its cylinder in a direction tangential to said second form cylinder and away from said 50 ink distributing mechanism.

45 55. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow movement of the same out of operative relation with its cylinder in a direction away from said point of convergence; and an ink fountain common to said ink distributing mechanisms disposed between the paths of movement of said ink distributing mechanisms.

60 65. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow movement of the same out of operative relation with its cylinder in a direction away from said point of convergence; a second ink distributing mechanism for said second form cylinder disposed adjacent said point of convergence on said one side and between said first mentioned ink distributing mechanism and said second form cylinder; a support for said second ink distributing mechanism adapted to allow movement of the same out of operative relation with its cylinder in a direction tangential to said second form cylinder and away from said point of convergence; and an ink fountain common to said ink distributing mechanisms disposed between the paths of movement of said ink distributing mechanisms.

70 75 80 85 90 95 100 105 110 115 120 125 130. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow arcal movement of the same out of operative relation with its cylinder in a direction away from said point of convergence, the focal point of said arc being disposed at the distant end of said ink distributing mechanism relatively to said point of convergence; a second ink distributing mechanism for said second form cylinder disposed adjacent said point of convergence on said one side and between said first mentioned ink distributing mechanism and said second form cylinder; a support for said second ink distributing mechanism adapted to allow movement of the same out of operative relation with its cylinder in a direction tangential to said second form cylinder and away from said ink distributing mechanism.

point of convergence; and an ink fountain common to said ink distributing mechanisms disposed between the paths of movement of said ink distributing mechanisms.

- 5 38. A printing press including a form cylinder; a second form cylinder disposed in printing relation with said first mentioned form cylinder; an ink distributing mechanism for said first form cylinder disposed 10 adjacent and on one side of the point of convergence of the peripheries of said cylinders; a support for said ink distributing mechanism adapted to allow movement of the same out of operative relation with its cylinder in a direction away from said point of convergence; a second ink distributing mechanism for said second form cylinder disposed adjacent said point of convergence on said one side and between said first mentioned ink distributing mechanism and said second form cylinder; a support for said second ink distributing mechanism adapted to allow movement of the same out of operative relation with its cylinder in a direction 15 away from said point of convergence; an ink fountain; and a ductor roller in operable relation therewith, said ink fountain and ductor roller being common to said ink distributing mechanisms and disposed between the paths of movement of said ink distributing mechanisms.

- 20 39. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow arcal movement of the same out of operative relation with its cylinder in a direction away from said point of convergence, the focal point of said arc being disposed at the distant end of said ink distributing mechanism relatively to said point of convergence; a second ink distributing mechanism for said second form cylinder disposed adjacent said point of convergence on said one side and between said first mentioned ink distributing mechanism and said second form cylinder; a support for said second ink distributing mechanism adapted to allow movement of the same out of operative relation with its cylinder in a direction 25 tangential to said second form cylinder and away from said point of convergence; an ink fountain; and a ductor roller in operable relation therewith, said ink fountain and ductor roller being common to said ink distributing mechanisms and disposed between the paths of movement of said ink distributing mechanisms.

- 30 40. A printing press including a form cylinder; a second form cylinder disposed in printing relation with said first mentioned

form cylinder; an ink distributing mechanism for said first form cylinder disposed adjacent and on one side of the point of convergence of the peripheries of said cylinders; a support for said ink distributing mechanism adapted to allow movement of the same out of operative relation with its cylinder in a direction away from said point of convergence; a second ink distributing mechanism for said second form cylinder disposed adjacent said point of convergence on said one side and between said first mentioned ink distributing mechanism and said second form cylinder; a support for said second ink distributing mechanism adapted to allow movement of the same out of operative relation with its cylinder in a direction tangential to said second form cylinder and away from said point of convergence; an ink fountain; and a ductor roller in operable relation therewith, said ink fountain and ductor roller being common to said ink distributing mechanisms and disposed between the paths of movement of said ink distributing mechanisms.

35 41. A printing press including a form cylinder; a second form cylinder disposed in printing relation with said first mentioned form cylinder; an ink distributing mechanism for said first form cylinder disposed adjacent and on one side of the point of convergence of the peripheries of said cylinders; a support for said ink distributing mechanism adapted to allow arcal movement of the same out of operative relation with its cylinder in a direction away from said point of convergence, the focal point of said arc being disposed at the distant end of said ink distributing mechanism relatively to said point of convergence; a second ink distributing mechanism for said second form cylinder disposed adjacent said point of convergence on said one side and between said first mentioned ink distributing mechanism and said second form cylinder; a support for said second ink distributing mechanism adapted to allow movement of the same out of operative relation with its cylinder in a direction 40 tangential to said second form cylinder and away from said point of convergence; an ink fountain; and a ductor roller in operable relation therewith, said ink fountain and ductor roller being common to said ink distributing mechanisms and disposed between the paths of movement of said ink distributing mechanisms.

45 42. A printing press including a form cylinder; a second form cylinder in printing relation therewith; ink distributing mechanism for the second form cylinder adapted to be adjusted to ink the first form cylinder.

50 43. A printing press including a form cylinder; a second form cylinder in printing relation therewith; ink distributing mecha-

nism for the first form cylinder; ink distributing mechanism for the second form cylinder; a mounting for the form roller of said first mentioned inking mechanism 5 which is nearest the point of convergence of said cylinders adapted to allow adjustment of said roller to bring the same into inking relation with the second form cylinder.

44. A printing press including an ink distributing mechanism; a form cylinder in operative relation therewith and movable out of operative relation with the same; a second form cylinder in printing relation therewith; ink distributing mechanism for 10 the second form cylinder adapted to be adjusted to ink the first form cylinder and so disposed that the movement of said first form cylinder moves out of operative relation therewith when it moves out of operative relation with its ink distributing mechanism.

45. A printing press including an ink distributing mechanism; a form cylinder in operative relation with the same and movable 25 out of operative relation therewith; a second form cylinder in printing relation with said first form cylinder and disposed to allow said first form cylinder to move out of printing relation therewith in the same 30 movement as it moves out of operative relation with said first ink distributing mechanism; a second ink distributing mechanism for the second cylinder adapted to be adjusted to ink said first form cylinder and 35 disposed to allow said first form cylinder to move out of inking relation therewith in the

same movement as it moves out of operative relation with said first ink distributing mechanism.

46. A printing press including a form 40 cylinder; a second form cylinder; and ink distributing mechanism for one form cylinder including a roller adapted to be adjusted to ink either of said form cylinders.

47. A printing press including a form 45 cylinder; an ink distributing mechanism therefor; a second form cylinder; ink distributing mechanism for the second form cylinder adapted to be adjusted to ink the first form cylinder to supplement said first 50 mentioned ink distributing mechanism when adjusted to ink said first mentioned cylinder.

48. A printing press including a form cylinder; an ink distributing mechanism therefor; a second form cylinder; ink 55 distributing mechanism for the second form cylinder including a plurality of form rollers and an adjustable support for one form roller adapted to be adjusted to ink either cylinder to supplement said first mentioned ink distributing mechanism when adjusted to ink said first mentioned cylinder.

49. A printing press including a form cylinder; an ink distributing mechanism therefor; a second form cylinder in printing 60 relation therewith; ink distributing mechanism for the second form cylinder adapted to be adjusted to ink the first form cylinder.

In witness whereof I have hereunto affixed my signature this 23rd day of September, A. D. 1918.

ROBERT MIEHLE.
